INVENTOR.

Robert Wilson,

BY

Geo. P. Kimmel. ATTORNEY.

UNITED STATES PATENT OFFICE.

ROBERT WILSON, OF SEANOR, PENNSYLVANIA.

RUBBER VALVE FOR PLUNGER PUMPS.

Application filed July 23, 1927. Serial No. 209,012.

This invention relates to a valve designed primarily for use in connection with plunger pumps employed in mines, but it is to be understood that a valve in accordance with 5 this invention may be used in any connection for which it is found applicable, and the invention has for its object to provide, in a manner as hereinafter set forth, for reducing the wear of the inner edge of the 10 valve body as it moves on the piston thereby resulting in overcoming the necessity to replace the valve at short intervals, increasing the life of the valve and materially decreasing the cost of maintenance and further reducing the stoppage of operation of 15 the pump to a material extent.

Further objects of the invention are to provide, in a manner as hereinafter set forth, a valve which is simple in its construction and arrangement, strong, durable, 20 compact, thoroughly efficient in its use, conveniently installed with respect to a piston or plunger, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claim hereunto appended.

In the drawings wherein like reference characters denote corresponding parts throughout the several views:

Figure 1 is an elevation of a valve in accordance with this invention.

Figure 2 is a cross sectional view thereof.

A valve in accordance with this invention, comprises a body portion 1 in the form of an annulus and with its inner edge indicated at 2 and its outer edge at 3. The 45 width of the body portion 1 from its inner to its outer edge can be as desired. The body portion 1 is also of appropriate diameter, and is constructed of resilient material,

preferably rubber and which possesses a clamping characteristic with respect to the 50 piston, with which the valve is used, to provide a seal tight joint and in order to secure compression.

Embedded in the body portion 1 is a metallic ring 4 having its inner diameter 55 corresponding to the inner diameter of the body portion 1 and the ring 4 has its inner face flush with the inner edge 2 of the body portion 1. The thickness of the body portion of the ring 4 is as desired and the said ring 4 is positioned centrally with respect to the inner edge 2 of the body portion 1. The metal employed for the ring 4 possesses a characteristic to resist the action of sulphur water or in other words the ring 4 is 65 constructed of corrosion resisting metal and acts to prevent the inner edge 2 of the body portion 1 from wearing over size and out of shape. The ring 4 is moulded in the body portion 1. The ring 4 materially reduces 70 the wearing off of the inner edge 2 of the body portion 1 and the result is that the life of the valve is materially increased.

It is thought the many advantages of a valve, in accordance with this invention and for the purpose set forth, can be readily understood, and although the preferred embodiment of the invention is as illustrated and described, yet it is to be understood that changes in the details of construction can 80 be had which will fall within the scope of the invention as claimed.

What I claim is:

A valve comprising a compressible body portion in the form of an annulus, and a 85 corrosion resisting metallic ring embedded in said body portion and having its inner edge flush throughout with the inner edge of the annulus, said ring spaced from both faces of the annulus, having its outer diameter materially less than the outer diameter 90 of the annulus, of rectangular cross section and of uniform cross sectional width.

In testimony whereof, I affix my signature hereto.

ROBERT WILSON.
